UNITED STATES PATENT OFFICE.

EDWARD DANIEL FITZPATRICK, OF OMAHA, NEBRASKA.

MECHANICAL MATCH-LIGHTER.

1,089,199.

Specification of Letters Patent.

Patented Mar. 3, 1914.

Application filed May 22, 1913. Serial No. 769,197.

To all whom it may concern:

Be it known that I, EDWARD D. FITZPATRICK, a citizen of the United States, and a resident of Omaha, in the county of Douglas and State of Nebraska, have invented a new and Improved Mechanical Match-Lighter, of which the following is a full, clear, and exact description.

Among the principal objects which the present invention has in view are: to provide a time-released mechanism to ignite a match by abrading the head thereof; to provide an alarm clock with means for lighting a match by abrasively engaging the head thereof; and to provide a clock mechanism of the character mentioned with means for holding a match in operative position, and with means for igniting the same by abrading the head thereof when released by said clock mechanism.

One embodiment of the present invention is shown in the accompanying drawings, in which

Figure 1 is a pictorial view showing a clock of conventional shape holding a match in operative position, with means for igniting the same, and the end of a fuse or lighter to convey the flame to the remote point; Fig. 2 is a rear view of said clock, a portion of the back of the clock case being cut away to show the arrangement of the match-igniting mechanism; Fig. 3 is a vertical section taken on the line 3—3 in Fig. 2; Fig. 4 is a horizontal section taken on the line 4—4 in Fig. 2; Fig. 5 is a detail view showing the shape of a match-striking disk employed by me; Fig. 6 is a sectional elevation of a fragment of said clock case and gear train thereof, showing in conjunction therewith a modified form of the invention; Fig. 7 is a side view of the same, showing the scratch plate as engaged with a match; Fig. 8 is a similar view, showing the scratch-plate as disengaged from the match; Fig. 9 is a detail view in section, taken on the staggered line 9—9 in Fig. 7; Fig. 10 is a sectional elevation of a clock case and a further modified construction embodying the invention; Fig. 11 is a top view of a fragment of the construction shown in Fig. 10; Fig. 12 is a cross section of the scratch-plate and housing therefor, taken on the line 12—12 in Fig. 10.

In the accompanying drawings, several forms of mechanism are shown, the func-

tion of which is to scratch a match said mechanisms being arranged to operate at a predetermined time. In the preferred form of mechanism, shown in Figs. 1 to 5 inclusive, a disk 20 is employed. The disk 20 is provided with a peripheral recess 21, which recess normally registers with, to rest above, a match 22, when set in position. The match 22 is held in position, as shown in Figs. 1 and 2 of the drawings, by a small loop 23. The loop is formed by partly severing a section of, and pressing the same outward from, the back 24 of a clock case 25. The under surface of the disk 20 is roughened to provide an abrasive surface. The disk 20 may be constructed of any suitable material, such as a rasp-faced metal disk, but I prefer to employ a sand-paper disk. The disk 20 is held rigidly on a vertical arbor 26, being clamped thereto by a screw nut 27, the threads whereof register with threads on an extension 28. The arbor 26 is mounted in bearings formed in the case 25, and in a bracket 29 in the structural frame of a clock gear train having an alarm mechanism of conventional form and construction. A wheel 45 and a pin 47 are arranged to permit a spring latch 30 to release the arbor 26. The latch 30 is suitably mounted on the frame of the clock gear train, to normally engage the teeth of a spur wheel 31. The wheel 31 is loosely mounted on the arbor 26. Fixedly mounted on the arbor 26 is a small ratchet wheel 32. A pawl 33 is pivotally mounted on the wheel 31, the tooth whereof engages the teeth on the ratchet wheel 32 as the same is turned when the arbor 26 is rotated to wind a spring 34. The pawl 33 is held in engagement with the teeth of the ratchet wheel 32 by means of a wire spring 35. The arbor 26 is rotated by means of the spiral spring 34, one end whereof is connected with said arbor, while the other end is fastened to a convenient part of the frame of the clock gear train. The wheel 31 is released when the wheel 45 is rotated by the gear train of the clock with which it is engaged, to a position where the pin 47 falls into the nick or opening 46 in the hub of said wheel. The wheel 45 is loosely mounted on the shaft 48 to slide thereon. The spring latch 30 presses said wheel 45 outward, said spring pressing upon the bearing ring 44. The shaft 48 and pin 47 thereon are stationary.

The operation is as follows:—The arbor 26 is manually rotated by means of a handle 36 to wind the spring 34 on said arbor. The winding is continued until the recess 21 of the disk 20 registers with the opening 37 in the rim of the clock frame and above the loop 23. The match 22 is now inserted in the loop 23, to extend upward through the opening 37. Said match is then adjusted to present the head thereof to be acted on by the disk 20. The alarm mechanism having been set, the clock is then disposed in convenient position adjacent a fuse or wick 38. The fuse or wick 38 is extended from and disposed in the kindling. The invention is used primarily in conjunction with what may be termed domestic fires, which fires are, as a rule, "laid" at night, for lighting in the morning. The clock bearing the match 22, disk 20 and parts connected therewith having been placed so that the match, when struck, will ignite the wick 38, the mechanism thereafter and at the predetermined time, moves the latch 30 from engagement with the wheel 31, permitting the spring 34 to rapidly rotate one complete revolution of the disk 20. The abrading surface of the disk being moved thus rapidly over the sensitive head of the match, operates to ignite or flash the same. The flame from the match thereafter mounts upward through the recess 21 in the disk 20 and ignites the wick 38. The flame follows the wick 38 into the midst of the kindling 35 of the fire, to ignite the same, thereby starting the fire without manual handling thereof.

The modified form of the invention shown in Figs. 6 to 9 inclusive employs in place of the disk 20 a curved, elongated, metal scratch plate 39. The plate 39 is mounted on an arm 40, which is pivoted by means of a pin 41 on the frame of the clock gear train. The arm 40 continues beyond the pin 41, and is bent to assume a horizontal position when the plate 39 is moved forward over the match 22, see Figs. 6 and 7 of the drawings. The lower and short end of the arm 40 is normally held by a trigger 42. The trigger 42 is provided with a short arm 43, which normally bears against a bearing ring 44 on the wheel 45. The trigger 42 is pivoted and held in normal position by a flat spring 59. The wheel 45 is normally connected with the clock gear train to be moved thereby at an ascertained ratio. The hub of the wheel 45 is cut away to form an opening 46 to register with a pin 47. The pin 47 is set up from a stationary shaft 48 extending between the sides of the clock gear train mounting frame. Interposed between said frame and the wheel 45 is the spring latch 30. When the wheel is moved outward by the spring 30 a spring 50 trips the trigger. The spring 50 draws backward the plate 39 from the position shown in Fig. 7 to

the position shown in Fig. 8, igniting the head of the match 22. By passing beyond the match, the said plate permits the flame of said match to mount upward to ignite the wick 38. To set the match 22 and plate 39, when employing the modified construction, the match 22 is first adjusted in the loop 23, and depressed therein out of contact with the plate 39 when the same is moved into the said position, as seen in Fig. 7 of the drawings. When the plate 39 is thus moved, the wheel 45 is pressed inward against the short arm 43 of the trigger 42, and against the spring 30, flattening the same, to permit the hub of the wheel 45 to pass inside of the pin 47. In this last position, the teeth of the wheel 45 will register with and engage the teeth of one of the wheels of the clock gear train. When now permitted, the spring 30 presses outward on the wheel 45 to hold the hub thereof against the side of the pin 47. The match 22 is then lifted until the head of said match presses firmly against the roughened under side of the plate 39. The clock is then placed in position where the flame mounting from the match 22 will ignite the wick 38.

In the modified form of the invention shown in Figs. 10 to 12 inclusive, the match 22 is held in a tube 51, and rests therein, at the lower end thereof, upon a short hook 52 formed by overturning the end of a wire slide 53. The slide 53 is mounted in guide eyelets 54 on the side of the tube 51. The tube 51 is rigidly mounted on a tubular bearing 55, which is pivotally mounted on a shaft 56, on which it is rotated by a wrapped spring 57. The ends of the spring 57 are suitably anchored, one end being turned behind the tube 51, and the other end engaging a portion of the frame of the clock gear train. The tubular bearing 55 is provided with a notched disk 58, with the notch of which the end of the latch spring 30 normally engages, to hold the tubular bearing 55 and the tube 51 in the alert position shown in Figs. 10 and 11. The spring 30 is held in the notch of the disk 58 by the wheel 45. By means of the modified form of the invention now being described, the match is drawn across the spring striker plate 60. The plate 60 is provided with sides 61, which form a housing or runway for the match and the tube 51 holding the same. At the end of the operation of striking the match 22, or of the rotation of the bearing 55, the match is disposed as shown by broken lines in Fig. 10 of the drawings.

When setting the lighter constructed in accordance with the last-described modification, the match is placed in the tube 51 when the same is in the position shown by the broken lines in Fig. 10. The slide 53 is depressed or moved toward the bearing 55. The match 22 is permitted to enter deeply

into the tube 51 to prevent contact between the roughened surface of the plate 60 and the sensitive end of the match. The tube 51 is then pressed inward under the plate 60, 5 until the nick in the disk 58 is brought in register with the end of the spring 30. This permits the engagement of said spring and nick by pressing the wheel 45 back against said spring, said wheel being rotated to 10 carry the pin 47 out of the opening 46. This locks the tube 51 in the alert position shown in full lines in Fig. 10. Prior to locking the tube 51, the slide 58 is lifted until the head of the match is pressed against the 15 under side of the plate 60 at the rear end thereof. When now the spring 57 is permitted, it draws rapidly forward the tube 51 and the match 22 carried therein, to the position shown in broken lines in Fig. 10, 20 in doing which, the match is struck, and the flame mounting therefrom ignites the wick 38 in the yoke 66.

Each block is provided with a bent arm 62, having a fastening portion 63 and a 25 yoke 64. The yoke 64 is provided to hold the fuse or wick 38. In the forms where the housings 65 are provided, a short yoke 66 is

employed to hold the fuse or wick 38, as shown in the drawings.

Claim:

In combination, a clock having a frame provided with an annular flange slotted to permit the insertion of a match, and a loop disposed in alinement with said slot, said loop being integrally connected with the 35 back of said frame; a rotary member operatively mounted partially within said frame; an abrasive member mounted on said rotary member to extend above said slot and loop to abrade a match when held in said loop; 40 a spring motor device for rotating said rotary member, said device being mounted on said member, within said frame; a latch to hold said member against rotation by said device; and means operatively connected 45 with the mechanism of said clock, for releasing said latch.

In testimony whereof I have signed my name to this specification in the presence of two subscribing witnesses.

EDWARD DANIEL FITZPATRICK.
